DESIGN FOR A COMBINED BROOCH AND LOCKET

Victor Silson, New York, N. Y.

Application July 9, 1941, Serial No. 101,988

Term of patent 3½ years

To all whom it may concern:

Be it known that I, Victor Silson, a subject of the King of Great Britain, residing in New York city, county of New York, and State of New York, have invented a new, original, and ornamental Design for a Combined Brooch and Locket, of which the following is a specification, reference being had to the accompanying drawing, forming part thereof.

Fig. 1 is a plan view of a combined brooch and locket showing my new design.

Fig. 2 is an edge view thereof.

Fig. 3 is a plan view showing the locket portion in open position.

I claim:

The ornamental design for a combined brooch and locket, substantially as shown.

VICTOR SILSON.
